(57) **CLAIM**

The ornamental design for a beverage bottle, as shown and described.

DESCRIPTION

FIG. 1 is a top perspective view of a beverage bottle showing my new design.

FIG. 2 is a front elevational view thereof.

FIG. 3 is a back elevational view thereof.

FIG. 4 is a top plan view thereof.

FIG. 5 is a bottom plan view thereof.

FIG. 6 is a right side elevational view thereof.

FIG. 7 is a left side elevational view thereof; and,

FIG. 8 is a cross-sectional view thereof taken along line 8-8 in FIG. 1.

The broken lines in the drawings depict portions of the beverage bottle that form no part of the claimed design.

1 Claim, 2 Drawing Sheets
